UNITED STATES PATENT OFFICE

118,581

DESIGN FOR A FLOOR SURFACING MACHINE

William E. Holt, Livingston, N. J.

Application April 4, 1939, Serial No. 84,029

Term of patent 7 years

To all whom it may concern:

Be it known that I, William E. Holt, a citizen of the United States, residing at Livingston, in the county of Essex and State of New Jersey, have invented a new, original, and ornamental Design for a Floor Surfacing Machine, of which the following is a specification, reference being had to the accompanying drawing, forming part thereof.

Fig. 1 is a perspective view of a floor surfacing machine, showing my new design; and
Fig. 2 is a perspective view looking at the opposite side of the machine.

I claim:

The ornamental design for a floor surfacing machine, as shown.

WILLIAM E. HOLT.
